UNITED STATES PATENT OFFICE.

CHARLES H. DIETZ, OF CHICAGO, ILLINOIS, ASSIGNOR TO UNITED STATES TENT & AWNING COMPANY, OF CHICAGO, ILLINOIS, A CORPORATION OF ILLINOIS.

DESIGN FOR AN AWNING ARM.

Application filed January 28, 1928. Serial No. 25,072. Term of patent 7 years.

To all whom it may concern:

Be it known that I, CHARLES H. DIETZ, a citizen of the United States, and a resident of Chicago, county of Cook, and State of Illinois, have invented a new, original, and ornamental Design for an Awning Arm, of which the following is a specification, reference being had to the accompanying drawing, forming a part thereof, and wherein—

Fig. 1 is a view in side elevation of an awning arm embodying my design and Fig. 2 is a top plan view thereof.

I claim:

The ornamental design for an awning arm substantially as shown.

CHARLES H. DIETZ.
